UNITED STATES PATENT OFFICE

167,625

POWDER BOX OR THE LIKE

Arnold E. Fischel, Brooklyn, N. Y.

Application January 10, 1952, Serial No. 17,998

Term of patent 3½ years

(Cl. D86—10)

To all whom it may concern:

Be it known that I, Arnold E. Fischel, a citizen of the United States of America and a resident of Brooklyn, county of Kings, and State of New York, have invented a new, original, and ornamental design for a Powder Box or the like, of which the following is a specification, reference being had to the accompanying drawing forming part thereof, in which:

Fig. 1 is a plan view of a powder box or the like showing my new design;

Fig. 2 is an end view thereof;

Fig. 3 is a front view thereof;

Fig. 4 is a sectional view taken on lines 4—4 of Fig. 2, and looking in the direction of the arrows; and,

Fig. 5 is a perspective view of the lid of the powder box.

I claim:

The ornamental design for a powder box or the like, as shown.

ARNOLD E. FISCHEL.
